UNITED STATES PATENT OFFICE.

FRANCIS KEIL, OF NEW YORK, N. Y., ASSIGNOR TO FRANCIS KEIL & SON, OF NEW YORK N. Y.,
A FIRM.

HINGE.

No. 920,960.

Specification of Letters Patent.

Patented May 11, 1909.

Original application filed February 27, 1905, Serial No. 247,583. Divided and this application filed December 7, 1905. Serial No. 290,825.

To all whom it may concern:

Be it known that I, FRANCIS KEIL, a citizen of the United States of America, and a resident of New York, in the county of New York and State of New York, have invented a certain new and useful Hinge, of which the following is a specification, the same being a full, clear, and exact description of the invention such as will enable others skilled in the art to which it appertains to make and use the same.

This invention relates to appliances designed for purposes of supporting movable articles, as swinging doors and the like, and in particular to hinges for doors for refrigerators, ice-boxes, and other structures where air-tight doors are required, and it has for its object to provide a hinge simple and inexpensive in construction, readily applied and operated and efficient in practical use.

With this object in view the invention consists in certain novel features of construction and combination and arrangement of parts, all of which will be hereinafter described and specifically pointed out in the drawings which accompany and form a part of this specification, and in which—

Figure 1 represents an elevation of a door equipped with this invention; Fig. 2 is a plan view of the same; and Figs. 3, 4, 5, 6, 7 and 8 are views in detail of the operating parts of the members of the hinge.

Like letters of reference indicate like parts in all the views.

Referring particularly to the drawings A, in the present embodiment of the invention, denotes a door, and B the jamb thereof.

To the jamb B is ordinarily secured the keeper C—having a nosing C¹—and also one member of leaf D of a hinge, the other member, strap or leaf D¹ of which is attached to the door A. To the said door is also preferably secured any suitable latch as the latch consisting of a casing E² and upper member E pivoted to the same at e so as to work in a vertical direction, and a lower member E¹ hinged to the member E. The latch members may be actuated by lifting the rod F by the manual controlling device F² or the treadles K or K¹ in order to release the latch so as to open the door.

A rod H provided with a controlling manually actuated device, as a handle H², is

mounted eccentrically in the circular journals H¹, which latter elements serve as a pintle of the hinge member D¹. The said journals H¹ work respectively in circular channels or sockets formed in the members or leaves D of the hinge. The rod H is entered into the smaller circular channel or socket of the member D¹ and forms the pintle thereof. The said rod is preferably used in connection with a plurality of hinges, three being shown in the present instance, the said rod H being mounted loosely in the hinge member D¹.

The member D of the hinge containing the journal H¹ and the eccentrically located rod H are shown separately in Figs. 3 to 5. The rod H is fixed to two journals H¹ the upper one shown in Fig. 4 and the lower one represented in Fig. 6, the latter one being provided with a manual actuating part of handle H². These two journals work, in use, in the member D within the orifices or sockets indicated by dotted lines in Fig. 5.

When it is desired to force the inner edge of the door into the jamb B, the rod H is manipulated by means of the handle H², and the journal H¹ will, upon the said handle being pushed to one side, force the members or leaves D¹ of the hinges in an inward direction as regards the leaves D, and the inner edge of the door A will consequently be thus crowded or wedged into the jamb. It will be observed that when the door A is opened the rod H and journals H¹ become self acting, as the handle H² lies against or near the door when the latter is closed, and the movement of the door in opening causes the handle to move around on its axis, and the rod H in its rotation causes the leaves D¹ of the hinges to move not only radially but also with an advance movement as regards the other member of the hinge, that is to say, if the handle H² were not employed, the leaf D¹ would swing radially around on the pintle formed by the rod H in the ordinary manner, but in cases where the door pushes the handle H² along, the said handle causes the rod H¹ to rotate the journals H¹, and, on account of the eccentric location of the said rod, it is moved in a forward direction.

I do not claim in this application the specific construction of the latch herein shown

and described, as the same is claimed in my application Serial No. 247,588, filed Feb. 27, 1905, of which this is a division.

As it is evident that many changes in the construction, form, proportion and relative arrangement of parts might be resorted to without departing from the spirit and scope of my invention, I would have it understood that I do not restrict myself to the particular construction and arrangement of parts shown and described, but that such changes and equivalents may be substituted therefor, and that

What I claim as my invention is:

A hinge consisting of two members or leaves, one stationary hinge leaf having a circular socket or bearing, and the other movable hinge member having a similar circular socket smaller in diameter, a journal

or pintle located in the socket of the stationary member and adapted to support the other hinge member, a rod eccentrically located in and attached to said pintle and adapted to rotate therewith and extending through the socket of the movable member to form a pintle therefor, and a manually actuated device to control the said rod, whereby, upon manipulation of the latter, the door may be moved forward and backward, and also swung in a circular direction.

In testimony of the foregoing specification I do hereby sign the same in the city of New York county of New York State of New York this 10th day of October 1905.

FRANCIS KEIL.
